UNITED STATES PATENT OFFICE.

ELMER E. LANE, OF DANVERS, MASSACHUSETTS, ASSIGNOR TO HARRY H. BECKWITH,
OF BROCKLINE, MASSACHUSETTS.

WORK-FEEDING MECHANISM.

Application filed October 20, 1921. Serial No. 508,995.

This invention relates to work feeding mechanisms having been designed more particularly for skiving machines, though all or certain features thereof might be found desirable in connection with machines for different purposes.

In such feeding mechanisms a series of narrow toothed wheels is sometimes employed for engaging the work, the edges of 10 the teeth extending parallel to the axis of the wheels. When this construction is employed for machines for skiving shoe stiffener parts such as are now commonly made of a felt composition impregnated with 15 materials which soften under the influence of heat and which are generally friable, it is found that these wheels break off particles from the edge of the chip removed by the skiving knife, and that instead of 20 passing out of the machine with the chip they often pass along with the blank. During the further treatment of the blanks within the machines these particles often stick to the face thereof and become partially incorporated therein, forming projections which must be removed before incorporation into the shoe to prevent them from 25 showing through the upper, especially when the lighter grades of upper leather are employed. For this reason much time and 30 attention is required to inspect the skived blanks and remove these particles, and often they are not detected until they have 35 been incorporated in the shoe.

One feature of the present invention, therefore relates to a construction of toothed feed wheel which does not cause the breaking off of such particles.

A further undesirable characteristic of 40 the usual toothed wheels above mentioned is that as they are used the spaces between the teeth become clogged with matter from the material fed causing them to act more and more as solid faced wheels, decreasing 45 their effective hold on the work and necessitating frequent adjustments of the operating parts of the machine for proper operation.

A further feature of the invention relates 50 to a construction whereby the wheels shall be self-cleaning so that their action shall be

substantially uniform at all times and frequent adjustments of the machine shall not be required.

Co-operating with the feed roll which 55 carries a plurality of these toothed wheels a recessed matrice roll is employed, the recess in the roll defining the portion of the blank to be removed in the skiving operation. This invention further contemplates a novel 60 construction by which the relative angular position of the recess may be adjusted so that the cooperating rolls may cause the blanks to be properly presented to the skiving knife. 65

Further objects and advantageous details and combinations of parts will appear from a more complete description of an embodiment of this invention shown in the accompanying drawings in which 70

Figure 1 is a vertical detail view partly in section of the feeding mechanism.

Figure 2 is a plan of one of the feed disks or wheels formerly used.

Figure 3 is an edge view of the same. 75

Figures 4 and 5 are views similar to Figures 2 and 3, but showing the improved form of disk.

Figure 6 is a somewhat diagrammatic detail of a pair of adjacent feed teeth of the 80 improved form.

Figure 7 is a diagrammatic section on line 7-7 of Figure 6.

Figures 8 and 9 are plan views of the chip skived from a box toe stiffener blank 85 when using the feed disks of Figures 2 and 4, respectively.

Referring to Figure 1 at A is indicated a matrice roll and at B a feed roll cooperating therewith to feed the work to a skiving knife (not shown). The matrice roll A comprises a sleeve 1 recessed as shown at 2 to determine the shape and extent of material to be skived therefrom, the material being pressed against the roll and into the recess in a manner well known to those skilled in the art. 95

In alignment with the sleeve 1 are sleeves 3 and 4 journaled in fixed bearings 5 and 6 on the machine frame. The sleeves 1, 3, 100 and 4 are held for simultaneous rotation by keys 7 positioned in one of these sleeves,

herein shown as sleeve 1 interfitting grooves in the ends of the sleeves 3 and 4. All these sleeves might be made integral, if desired, but as it is sometimes desirable to use recessed portions of different contours and depths it is desirable for the sake of economy to make these sleeves separate.

Outwardly of the bearing 5 sleeve 3 is shown as provided with a pinion 8 fixed thereto for a purpose immaterial to this invention, and outwardly of this pinion is a collar 9 having a series of circumferential graduations or index marks as shown at 10. This collar is fixed to rotate with the sleeve 3. Cooperating with the index marks is a pointer 11 fixed at one end to the bearing 5. The sleeve 4, outwardly of the bearing 6, is shouldered as at 12, and journaled outwardly of this shoulder thereon is a driving wheel or gear 13. At either side of this gear are placed friction washers composed of fiber or other suitable material 14 and metallic collars or rings 15, the inner ring 15 abutting against the shoulder 12.

25. A bolt 16 having a head 17 at one end is passed through the various sleeves which are loosely mounted thereon, and adjacent the outer ring 15 is positioned a washer 18 bearing thereagainst. This end of the bolt 16 is threaded at 19 for the reception of a nut 20. By tightening up this nut the washer 18 is moved to clamp the rings 15, washers 14 and gear 13 against the shoulder 12, and to fix all these parts for simultaneous rotation with the sleeves 1, 3, and 4. These sleeves are designed to be rotated by means of a gear (not shown) meshing with the gear 13. Consequently the gear 13 is angularly fixed relative to the operative mechanisms of the machine. If it is desired to adjust the position of the recess 2 angularly it is only necessary to loosen the nut 20 and turn the sleeves the required distance which may be estimated by noting the divisions on the index 10 which pass the point 11. When the parts are in adjusted position, by tightening the nut 20 they are fixed to rotate in unison.

50. The feed roll B, between which and the roll A the work is passed, comprises sleeves 30 and 31 journaled in bearings 32 and 33 parallel to the bearings 5 and 6, a bolt 34 passing therethrough having a head 35 at one end and a nut 36 threaded on its opposite end. As shown this bolt is connected in the sleeve 31 in a similar manner to the bolt 16 and the sleeve 4, although this specific connection is immaterial to this roll since no rotative adjustment thereof is necessary.

55. Interposed between the inner ends of the sleeves 30 and 31 and keyed to rotate therewith is a series of toothed feed wheels comprising thin disks 25 spaced apart by means of washers 26 placed therebetween, washers 37 having keys 38 fitting corresponding ways

in the ends of the sleeves 30 and 31 being employed to lock the parts for simultaneous rotation.

The type of feed disk or wheel which has been commonly used in similar locations in other machines is that shown in Figures 2 and 3, in which each of the wheels or disks as 25^a has a series of peripheral teeth 40 having their edges extending parallel to the axis of the disk as 41. When feed wheels 73 of this type are used the edges 41 cut into the material fed so that the chip skived off when making box toe stiffeners appears substantially as shown in Figure 8. It will be noted in this figure that along the flatter edge of the chip, which edge is arranged transversely to the direction of feed as the blank passes through the machine and is the last part of the blank to pass between the rolls, portions are broken off, due both to the cutting effect of the teeth and the effort tending to feed the blank forward, such particles being indicated at *a*. These particles are liable to be carried along with the skived blanks and to be incorporated in the surface thereof. Particularly where these blanks are afterwards ironed or rolled these particles are liable to become partially embedded in the material in such a way as to project somewhat above the surface thereof so that if they are not removed before the blanks are inserted in the shoe projections are shown through the upper leather indicating the presence of these particles and seriously disfiguring the shoe.

In order to overcome this difficulty the feed disks in the present construction have their teeth cut out of parallelism with the axis of the feed roll as shown in Figures 1, 4, and 5, these teeth being indicated at 42, their narrow cutting edges 43 being inclined from the normal to the plane of the disk faces, or in other words, to the axis of the roll. These narrow edges or work-engaging portions being formed on the peripheries of the disks define a cylinder, the surface of which includes them all and to the adjacent surface elements of which they have a definite oblique relation, this relation being uniform for the cutting edges of any one disk. When disks of this type are used the markings on the skived chip appear as shown in Figure 9 in which they are inclined from the normal or transversely to the direction of feed of the work. Since the flatter edge of the blank is arranged transversely to the direction of feed through the machine, the teeth on the feeding roll will exert pressure on the blank along spaced lines arranged diagonally or obliquely to the edge of the blank. It is preferable to employ a series of such wheels the teeth of adjacent wheels being inclined oppositely so that the obliquity of each series of lines impressed on a blank is the reverse of that of

the next adjacent series, and a herring bone or zigzag effect is produced. This minimizes any tendency of the inclined teeth to feed the stock laterally as any tendency of certain wheels to move the work in one direction laterally is counteracted by an equal thrust of teeth oppositely inclined. With this construction it is found that the particles are not broken off from the edge of the chip since if they are near enough to the edge to cause a decided weakening at that point their inclined position causes them to cut through at one end, the material yielding to permit the teeth to pass without breaking.

With the teeth as constructed in Figure 2 it has been found that portions of the material fed gradually fill up the spaces between the teeth so that the disks become in effect solid and do not have the same feeding effect as when the teeth are clear. Because of this it is frequently necessary to adjust the relative position of operative parts of the machine to cause the skiving to be effected where desired or to take out and clean the disks. To overcome this difficulty the spaces or recesses between the teeth may be cut deeper at one side face of the disk than at the other, this being shown somewhat diagrammatically in Figures 6 and 7. This may be accomplished if desired by running a drill diagonally through the disk adjacent the teeth roots as shown in Figure 7. By this means the space at the deeper side of the wheel is not narrower than that of the other side as would be the case if the teeth faces were of V formation. This construction allows a ready escape for the material lodging between the teeth, the pressure of the material at the outer edges thereof causing any such matter to be pushed downwardly and laterally from between the teeth. As the washers 26 are of smaller diameter than the feed disks sufficient room is allowed laterally for the escape of such matter. This action, however, is further assisted by a series of fingers, shown in section at 50 in Figure 1, which extend between the disks and press the material fed between the rolls against the matrice roll so that it is forced within the recess 2. As the feed disks rotate it is evident that these fingers scrape off the material escaping from between the teeth and cause it to pass outwardly of the machine with the chip.

Having thus described an embodiment of the invention it should be evident that many changes and modifications might be made therein without departing from its spirit or scope as defined by the appended claims.

I claim:

1. A feed member comprising a series of

coaxial spaced disks having work-engaging portions defining a cylinder, the work-engaging portions of each individual disk having a common oblique relation to the adjacent surface elements of the cylinder. 65

2. A feed member comprising a series of coaxial spaced disks having work-engaging portions defining a cylinder, the work-engaging portions of each individual disk having a common oblique relation to the adjacent surface elements of the cylinder, and the work-engaging portions of successive 75 disks being in zigzag relation.

3. A feed member comprising a series of coaxial spaced disks having on their peripheries spaced work-engaging portions defining a cylinder, the work-engaging portions 80 of each individual disk having a common oblique relation to the adjacent surface elements of the cylinder, the spaces between successive work-engaging portions of any disk being of unequal depth at the opposite 85 faces of the disk.

4. A feed member comprising a series of coaxial spaced disks having on their peripheries spaced work-engaging portions defining a cylinder and having recesses between 90 successive work-engaging portions, the work-engaging portions of each individual disk having a common oblique relation to the adjacent surface elements of the cylinder, the work-engaging portions of successive 95 disks being in zigzag relation, and said recesses being deeper at one face of the disk than at the other.

5. Apparatus for feeding friable blanks comprising spaced work-engaging members, 100 each said member having means for engaging the blanks in a series of short lines, said series extending in the direction of feed, and said lines of a series being parallel to each other and oblique to the direction of 105 feed.

6. The method of feeding a friable blank having an edge arranged transversely of the direction of feed, which comprises exerting feeding pressure on said blank along series 110 of short parallel lines oblique to said edge, each series being spaced from the other series and extending in the direction of feed.

7. The method of feeding a friable blank having a relatively thin edge arranged transversely of the direction of feed, which comprises applying feeding pressure to the blank in spaced parallel series of contact lines, 115 each line being oblique to said edge and parallel to the other lines in its series, and the obliquity of the lines of each series being the reverse of that of the next adjacent series.

In testimony whereof I have affixed my signature.

ELMER E. LANE.
